UNITED STATES PATENT OFFICE.

JOHN MATTHEWS, OF NEW YORK, N. Y.; ELIZABETH MATTHEWS, GEORGE MATTHEWS, AND FREDERICK MATTHEWS, EXECUTORS OF SAID JOHN MATTHEWS, (DECEASED,) ALL OF SAME PLACE.

SODA-WATER APPARATUS.

SPECIFICATION forming part of Letters Patent No. 289,777, dated December 4, 1883.
Application filed January 20, 1883. (No model.)

To all whom it may concern:

Be it known that I, JOHN MATTHEWS, of New York city, county and State of New York, have invented an Improved Soda-Water Apparatus, of which the following is a specification.

The drawing represents a perspective view of my improved soda-water apparatus.

The object of this invention is to so arrange 10 the generators, purifiers, and receivers of soda-water apparatus that either one or more generators can be used separately or together in the making and diffusing of the gas and delivering the same into a suitable number of 15 cylinders or receivers—in other words, so that continuous action may be had, either one of two generators being at all times in communication with the receiver or receivers to be charged.

20 The invention consists in the new arrangement of connecting-pipes with reference to the generators, purifiers, and receivers, as hereinafter more fully described, whereby either one of two generators can be utilized at any 25 one time or both together, and either one cut out of connection when desired.

As heretofore made, the pipes connecting with the generators of such apparatus were mostly made of lead, and would bend or sag 30 in an unsightly manner, often interfering further with the working of the apparatus, and producing a stoppage and rendering accidents possible, to avoid which supports for such pipes were placed on the ceilings or other convenient position wherewith to maintain them 35 in place. By my invention the connecting-pipe is made self-supporting.

In the accompanying drawings, which illustrate two generators in connection with three 40 receivers, the letters A B represent the generators, each of which supports a vitriol-chamber, C D.

E F are the receivers or cylinders, each carrying a gas washer or purifier, G G' G''. From 45 the generator A rises a pipe, H, which extends over the gas-washers G G' G'', and then joins the generator B. In this pipe H are two

cocks—one, a, near its junction with the generator A, and the other, b, near its junction with the generator B. By a tubular bracket, 50 d, the pipe H, between these cocks a b, is supported on the gas-washer G, as shown. Another bracket, d', which, however, is not in communication with any tube or vessel, may be used to support the pipe H on the 55 vessel G².

The operation of this apparatus is as follows: After placing the necessary materials in one of the generators—say the generator A—and also in the fountains or receivers D E F, and 60 generating the gas in the generator, this gas is conducted by opening the valve a through the pipe H and bracket d into the gas-washer G, that stands on the fountain D. The gas passes from this gas-washer on fountain D 65 through a pipe, f, into gas-washer G' on fountain E, and thence through connecting-pipe g into the gas-washer G² on fountain F, and thence through the perpendicular pipe h into the pipe i, that leads into all the fountains 70 D E F. At the same time the valve b is closed. In the same way, when the generator B is to be used, the valve b is opened and the valve a closed. Suitable gages on the pipe H show the pressure in the generators, these 75 gages being also, by preference, connected through pipes e with the vitriol-chamber C, which pipes are known as the "equalizing-pipes." It will be seen that by this arrangement I am enabled to operate continuously. 80 When one generator is emptied, the other one is in operation. Meanwhile a full one is put in place of the empty one and put into action when the one last in use becomes emptied, and so on, and for special causes, if desired, both generators may be simultaneously thrown into action.

I claim—

1. The combination of two generators, A B, with a connecting-pipe, H, having the 90 two valves a b, and gas-washers G G' and fountains D E, &c., for operation substantially as herein shown and described.

2. The pipe or leader H, combined with

generators at each end, valves *a b* near each end, single tubular bracket *d*, the gas-washers *G G'*, and receivers *D E*, substantially as and for the purpose specified.

5 3. The combination of the generators *A B* with the connecting-pipe *H*, having valves *a b*, the bracket *d*, gas-washers *G G'*, receivers

D E, equalizing-pipes *e e*, and vitriol-chamber *C C*, substantially as and for the purpose specified.

JOHN MATTHEWS.
